UNITED STATES PATENT OFFICE.

JEROME I. VOGELER, OF BALTIMORE, MARYLAND.

BOTTLE.

SPECIFICATION forming part of Letters Patent No. 470,458, dated March 8, 1892.

Application filed March 7, 1891. Serial No. 384,117. (No model.)

To all whom it may concern:

Be it known that I, JEROME I. VOGELER, of Baltimore, Maryland, have invented certain Improvements in Bottles, of which the following is a specification.

This invention relates to a bottle intended especially for perfumery, which is adapted after the contents are exhausted to be used as a toy lantern, as will hereinafter fully appear.

In the description of the said invention which follows reference is made to the accompanying drawings, forming a part hereof, and in which—

15 Figure 1 is an exterior elevation of the improved bottle, and Fig. 2 a sectional elevation of the same.

In the said drawings, A represents the body of the bottle, which is of glass, preferably colored, and in the shape of a lantern, there being bars *a* molded on the exterior surface to represent the ordinary wire guard-bars. The body A is open at the top and bottom and provided with removable stoppers D and E, preferably of cork.

25 The upper end of the bottle is exteriorly threaded, and on it is screwed a perforated cap F, which represents the head of a lantern. The lower edge of this cap is provided with a flange *b*, to which the bail G is attached. The lower end of the body A is also threaded, as shown, and over it is screwed the perforated base H, which corresponds in shape with the base of a lantern.

35 When the device is in the condition shown in the drawings, it is a closed bottle and may

contain perfumery; but after the contents are exhausted the corks are removed and a taper *c* (shown in dotted lines in Fig. 2) inserted to illuminate the bottle and present the appearance of a lighted lantern.

To support the illuminating-taper, the base H is furnished with a cross-bar *d*, having a socket *e*, as shown in full lines in Fig. 2; but this bar and its socket may be placed above the lower edge of the base, as shown in dotted lines. The base H is perforated to admit air to the lighted taper after the manner of a lantern.

The object of screwing the cap and base to the body A is to admit of the ready removal of the corks as a preparatory step toward adapting the bottle as a lantern; but any other means of effecting their attachment may be employed without affecting the character of the invention.

This invention when adapted as a lantern is applicable to the decoration of trees and shrubbery at festivals which are held at night, and also to the illumination of Christmas trees.

I claim as my invention—

A bottle open at both ends and provided with removable stoppers, combined with a perforated top and an open base having a holder for a candle, substantially as and for the purpose specified.

JEROME I. VOGELER.
